ROLLING MILL POLISHER

Ralph H. Steughton, Steubenville, Ohio

Application May 6, 1932, Serial No. 609,733

2 Claims. (Cl. 51—253)

This invention relates to a rolling mill polisher and has for an object to provide an oscillating roll polisher for use on rolling mills. As is well known, rolling mills are used for rolling hot 5 steel, and this process causes scale and foreign matter upon the surface of the rolls causing uneven and rough surfaces on the rolls.

It is a further object of this invention to provide a roll polisher which will oscillate back 10 and forth across the surface of the rolling mill roll, smoothing the same, eliminating the rough surfaces and the scale and foreign matter deposited thereon.

Yet a further object of this invention is to provide a roll polisher which will bear harder on 15 the raised or hard streaks and less upon the soft or shallow spots, keeping the roll contour even and preventing the roll from getting out of round or indented with cut out streaks.

20 With the foregoing and other objects in view, as will hereinafter become apparent, this invention comprises the constructions, combinations, and arrangements of parts, hereinafter set forth and disclosed, and shown on the accompanying drawings. In the drawings,

Figure 1 is a side elevation of a rolling mill equipped with the polisher,

Figure 2 is an end view of same showing means for oscillating the polisher,

30 Figure 3 is a side elevation of one of the polishers,

Figure 4 is an end view of same,

Figure 5 is a diagrammatic view showing clearly the position of the polishers on the rolls,

35 Figure 6 is a plan view of the oscillating screw,

Figure 7 is a perspective view of one of the abrasives,

Figure 8 is a sectional view taken on line 3—8 of Figure 3, and

40 Figure 9 is a sectional view taken on line 9—9 of Figure 8.

There is shown at 10 the rolling mill to which this invention has been applied. The rolling mill 10 consists of a housing 11 and 12 having 45 the rolls 13 and 14 between which hot steel is rolled in the usual manner. As the hot steel is rolled between the rolls 13 and 14, scale and foreign matter is deposited on the surfaces of the rolls 13 and 14, causing them to become uneven 50 and making them unsuitable for further use.

This invention provides means for restoring a smooth and even contour of the rolls 13 and 14, placing them in condition for continued use.

The polisher 15 constituting this invention con-

55 polishing units 16 being provided for the upper roll 13 and polishing unit 17 being provided for the lower roll 14. The polishers 16 and 17 are substantially identical in construction, and are each mounted by means of the slots 18 for oscillation back and forth on extensions 19 and 20 of brackets 21 and 22. Each bracket 21 is pivotally supported to the housing 11 or 12 by means of a stud bolt 23 passing through a slot 24 in the arm 25 of the bracket 21. Another arm 26 60 of the bracket 21, which arm it will be noted is at right angles to the arm 25, has a weight 27 depending therefrom as by means of cables 28. The weight 27 pulling down on the arm 26 tends to force the polisher 16 against the surface of the 70 roll 13, as will be apparent in Figure 5.

In a similar way, the bracket 22 has an arm 29 seated on the stud bolt 30 of the housing 11 or 12, while an arm 31 at right angles to the arm 29, has a weight 32 secured thereto by the cables 33 75 passing over a pulley 34, the weight 32 thus tending to force the polisher 17 against the surface of roll 14. Each polisher 16 or 17 consists of a plurality of abrasive blocks 35 mounted in individual holders 36 and secured thereto by means 80 of stud screws 37 pressing against the bottom of the abrasive blocks 35. The holders 36 are each mounted in boxes 38, telescopic springs 39 being provided beneath each holder 36 and holding the holders against securing strips 39' which are 85 secured to the box 38 by screws 40. Projecting lugs 41 on holders 36 travel in groove 42 in the box 38, permitting the blocks 35 to depress against telescopic spring 39. Thus, when the polishers strike the raised portion on the surface of the 90 roll, the individual block 35 may be depressed into bracket box 38 against the spring 39, thus yielding for the particular high spots, thus at the same time, causing additional pressure to be exerted against the particular high spots and 95 reducing the same. The slots 18 in the polishers 16 and 17 are provided by projecting flanges 43 at each end of the bracket box 38. The bracket box 38 of each polisher 16 and 17 is provided with a socket 44 to receive the ball ends 45 of 100 connecting rod 46. The ball ends 47 formed on the other end of the connecting rod 46 are received in sockets formed in extensions 48 on the nut 49, the nut 49 being a reversible nut and traveling along the reversibly threaded screw 50 105 between the screw bearings 51 and 52. The bearings 51 and 52 are secured to the housing 11 by means of bolts 53, the bolts 53 also acting as guides for the nut 49 through the intermediary of the extension 48.

The screw 50 has secured thereto a bevelled gear 54 connecting with another bevelled gear 55 mounted on a shaft 56. The shaft 56 is supported in a bearing 57 on a bracket 58 secured by stud bolt 59 to the housing 11. Mounted on the shaft 56 is a worm wheel 60 cooperating with the worm gear on the shaft 61 of the wheel 62. A belt 63 supplies power to the wheel 62 from any suitable source, such as the power wheel 64.

10 In operation, the power from the wheel 64 through the train of gears just described, rotates the screw 50 causing the nut 49 to travel back and forth thereon between the bearings 51 and 52. The connecting rods 46 causes the polishers 16 and 17 to travel back and forth on the extensions 19 and 20 of the brackets 21 and 22, the ball and socket joint at each end of the connecting rods 46 allowing the polishers 16 and 17 to be rotated against the rolls 13 and 14 by means of the 15 weights 27 and 28. Thus the polishers 16 and 17 as a whole oscillate back and forth across the surface of the rolls 13 and 14 as the same are rotated. Should a raised or hard spot on one 20 of the rolls come into contact with one of the individual abrasive blocks 35, that particular block 35 will be forced back into the bracket 25 box 38 against the telescopic spring 39, thus causing extra pressure on the raised spots and reducing the raised spots to the level or contour 30 of the roll.

The novel features and the operation of this device will be apparent from the foregoing description. While the device has been shown and the structure described in detail, it is obvious

35

that this is not to be considered limited to the exact form disclosed, and that changes may be made therein within the scope of what is claimed without departing from the spirit of the invention.

Having thus set forth and disclosed the nature of this invention, what is claimed is:

1. A roll polisher comprising an abrasive means, pivotal means for mounting said abrasive means on a rolling mill housing tending to force said abrasive means against the rolling mill rolls, an extension means on said mounting means, means for causing said abrasive means to oscillate across the roll surface, said oscillating means comprising an abrasive holding bracket 80 slideable on said extension means, and means for sliding said bracket on said extension means, said latter means comprising a rotatable reversibly threaded screw, a reversible nut mounted on said screw, and connecting rod means, said connecting rod means having ball and socket connections to 85 said nut and to said bracket.

2. In an oscillating rolling mill polisher, a bracket, a plurality of abrasive block holders mounted in said bracket, an individual abrasive 100 block in each holder, lug means on each holder, groove means in said bracket providing paths for said lug means permitting said holder to be depressed into said bracket, and telescopic spring means in said bracket beneath each individual holder yielding to permit said holder to enter said bracket and tending to force said holder outwardly of said bracket.
